UNITED STATES PATENT OFFICE.

JOSEPH DURHAM, OF ROZELLE, NEAR SYDNEY, NEW SOUTH WALES, AUSTRALIA.

RESILIENT MOUNTING FOR THE STYLUS HOLDER OF TALKING MACHINES.

Original application filed April 17, 1923, Serial No. 632,646, and in Australia October 14, 1922.

Divided and this application filed September 23, 1924. Serial No. 739,356.

This invention relates to an improved resilient and adjustable mounting for the stylus-holder of a talking machine, and it is a division of my United States patent application Serial No. 632,646, filed 17th April, 1923, which matured into Pat. No. 1,569,817 dated Jan. 12, 1926.

An object of the invention is to improve reproduction and obtain clearer tone, especially in the case of records that have been frequently used, and have developed a tendency to "blast" whilst being played in the machine.

The improved mounting for the stylus-holder comprises a U-shaped member, having two spring arms, the end portions of which are pivotally engaged by adjustable pivots carried by lugs that are formed on the sound-box of the machine. These lugs may be split and furnished with locking screws, whereby the pivots are retained in selected adjusted positions relatively to the arms of the U-shaped spring.

In the accompanying drawings:—

Figure 1 is a view illustrating the sound-box of a talking machine fitted with the improved resilient mounting for the stylus-holder.

Figure 2 is an enlarged view, partly in section, clearly showing the stylus-holder and its resilient mounting.

Figure 3 is a central sectional view through the stylus-holder.

Figure 4 is a view illustrating a construction, wherein the stylus-holder is sound-insulated from the sound-box.

Figure 5 is a view showing modified means for adjusting the tension of the spring arms.

In these views, 5 designates the sound-box of a talking machine, 6 the diaphragm, 7 the stylus-bar, 8 the stylus-holder, and 9 the stylus, which is detachably secured in position in customary manner by a screw 10.

A U-shaped spring 11 is affixed at its base portion by brazing or like means to the outer end of the stylus-holder 8, and it has a hole 12 accommodating a neck 13 formed at the outer socketed end of the stylus-holder—see Figure 3 of the drawings.

The arms of the U-shaped spring 11 are inclined slightly outwardly and they extend upwardly on opposite sides of the stylus-

holder 8 having their end portions accommodated in a recess provided between two split lugs 14, that are formed marginally on the sound-box 5. Locking screws 15 are adapted to close the split portions of said lugs, while adjustable pivot screws 16 are passed through said lugs in a direction at right angles to said locking screws, and they have pointed ends which are maintained in pivotal engagement with the end portions of the arms of the U-shaped spring 11.

The tension of the spring arms can thus be easily regulated, when desired, by loosening the locking screws 15 so as to cause the split lugs 14 to open sufficiently to permit ready adjustment of the pivot screws 16, when said screws 15 are again tightened to lock the pivot screws 16 in selected adjusted positions.

The flexibility of the arms of the U-shaped spring 11 automatically compensates for wear of the adjustable pivot screws 16, and allows for greater freedom of movement of the stylus-holder 8, relative to the sound box 5, than is possible with mountings now in use, thereby ensuring much clearer tone and generally improved reproduction.

In the construction illustrated in Figure 4 of the drawings, the arms of the U-shaped spring 11 are sound-insulated from the adjustable pivot screws 16 by means of pads 17 or alternatively strips of rubber or like non-resonant material, whereby the transmission of any extraneous sounds or vibrations to the stylus 9, stylus-holder 8 and stylus-bar 7 is entirely eliminated.

According to the modification illustrated by Figure 5, the adjustable pivot screws 16 and the locking screws 15 are dispensed with, and small bolts 18 having adjusting nuts 19 are employed in lieu thereof. In this construction the lugs 14 need not necessarily be split, but can be tapped as shown to accommodate the readily adjustable bolts 18.

Modifications in constructional details, in design and in arrangement may be made within the ambit of the invention as defined by the following claims.

What I do claim is:—

In a mounting for a stylus holder on a sound box, a sound box having parallel spaced lugs extending laterally therefrom, a block having a recess for mounting a stylus

therein, a stylus bar fixed in and carried by the block, a U-shaped member of resilient material having the legs diverging from the connecting portion thereof, pivots adjustably carried by the sound box lugs for engagement of the ends of the legs of the U-shaped member to pivotally support the

same, said block being engaged within said U-shaped member and secured to the connecting portion thereof with the legs of the U-shaped member free of and extending laterally of the block. 10

In testimony whereof I affix my signature.
JOSEPH DURHAM.
